UNITED STATES PATENT OFFICE.

JAMES H. RAND, OF NORTH TONAWANDA, NEW YORK.

INDEX-CARD.

1,294,947.

Specification of Letters Patent. Patented Feb. 18, 1919.

Application filed September 4, 1917. Serial No. 189,580.

To all whom it may concern:

Be it known that I, JAMES H. RAND, a citizen of the United States, residing at North Tonawanda, in the county of Niagara 5 and State of New York, have invented new and useful Improvements in Index-Cards, of which the following is a specification.

Where the groups or sections of ordinary card indexes contain a comparatively large 10 number of record cards or units, considerable time is required to find a desired card, and this is relatively true of smaller indexes.

The object of my invention is to so dispose or support the cards of the various 15 sections of the index as to greatly expedite reference to any one of them and to accomplish this without materially increasing the cost of the index.

20 In the accompanying drawings:

Figure 1 is a perspective view of a card index embodying the invention. Fig. 2 is a similar view of a number of the cards and the corresponding guide. Fig. 3 is a perspective rear view of one of the cards.

Similar characters of reference indicate corresponding parts throughout the several views.

1 indicates an ordinary drawer, box or 20 other suitable receptacle having a flat bottom and containing the record cards or like units 2. These cards are preferably arranged in removable groups or sections each of which is backed by a guide 3 bearing an 25 appropriate index-designation, as shown. On their faces, near their upper edges, the cards of each group bear names or other desired index-designations arranged alphabetically or consecutively, as shown. Each 30 card of a group is provided with a lip, ledge or projection 4, constructed and arranged to support the next card behind it at an elevation slightly above itself, so that the several cards of a group are held or disposed

in stepped or staggered order, as shown in 45 Fig. 2. These ledges may be cheaply formed by bending back the lower edges of the cards substantially at right angles to their body-portions, as shown. The cards are thus stepped or offset a distance equal 50 to the thickness of the cards.

By this construction and arrangement, upon removing a section from the receptacle, a given card thereof can be found and referred to almost instantly by holding the 55 pack in one hand and deflecting the stepped upper edges of the cards rearwardly with the other hand, the cards being allowed to slip past the thumb in rapid succession until the desired one is reached. Obviously, 60 this can be done much more quickly than by the common method of turning over a greater or less number of ordinary record cards. By placing the names or other designations near the tops of the cards, they 65 will be fully and clearly exposed by a comparatively slight springing of the cards, facilitating their location and at the same time avoiding excessive bending of the cards.

70 This improved construction has the further advantage that in cases where it is desirable to carry different sets or sections of record cards from place to place by various employees or attendants, the removed sections can be carried in the pocket and any 75 of their cards quickly referred to, in the manner above described.

I claim as my invention:

1. In a card index, a series of record 80 cards or the like, each having its lower edge bent at an angle to form a supporting lip for the adjacent card.
2. In a card index, a record card provided at its lower edge with a rearwardly bent 85 lip for supporting an adjacent card.

JAMES H. RAND.
